United States Patent Office.

JAMES T. PAGE, OF ROCHESTER, NEW YORK.

Design No. 4,941, dated May 23, 1871.

DESIGN FOR A BROILER.

The Schedule referred to in these Letters Patent and making part of the same.

To all whom it may concern:

Be it known that I, JAMES T. PAGE, of the city of Rochester, in the county of Monroe and State of New York, have invented and produced a new and original Design for Broilers, of which the following is a specification.

Nature of the Invention.

This invention consists of a flaring or angular body, made without a surmounting rim, and adapted to boiler-holes of different sizes, as hereinafter described.

General Description.

In the drawing—

Figure 1 is a perspective view.

Figure 2, a vertical section.

A represents the flaring or cone-shaped body which forms the broiler.

This body stands at such an angle and is of such a size as to fit the several sizes of boiler-holes in ordinary stoves and discharge the drippings inside. It is formed either round or oval in outline, as may be desired, to fit the round or oval openings in stoves.

B is the handle, and

C the grating, which may be applied in any desired manner.

An interior flange, attached to a vertical rim, has been before employed to throw the drippings in the stove, but in that case the flange is only an attachment, the rim forming the body of the broiler.

My invention consists in making the entire body of the broiler of angular or cone-shaped form.

This form is convenient in use, and is made at half the cost of the other.

Claim.

What I claim as my invention is—

The design for a broiler, as herein shown and described.

In witness whereof I have hereunto set my hand this 31st day of March, 1871.

JAMES T. PAGE.
